UNITED STATES PATENT OFFICE

2,685,790

WASH BOILER

Charles J. Brennan, Ottawa, Ontario, Canada

Application June 2, 1948, Serial No. 30,581

3 Claims. (Cl. 68—191)

1

This present invention relates to improvements in a wash boiler and appertains particularly to one having a steam-agitated false bottom or pulsator. It is a continuation-in-part of my co-pending application #785,582, filed November 13, 1947.

An object of the invention is to provide a steam pressure washing machine having a pulsator plate resting loosely on the bottom thereof designed both to vibrate and emit intermittent surges of steam when the contents of the vessel are brought to the boil.

A further object of the invention is to provide a wash boiler having a valved cover securely locked thereon whereby the pressure in the vessel may be increased with safety.

A further object of the invention is to provide a pressurized pulsator-type wash boiler having a perforated top plate, independent of the valved cover, that may be normally held in place by the locked-on cover but is capable also of being releasably secured in the vessel when said valved cover is removed.

A still further object of the invention is to provide a wash boiler of the nature and for the purpose described that is characterized by structural simplicity, durability, and efficiency and being capable of manufacture at reasonable cost is thereby rendered commercially desirable.

To the accomplishment of these and related objects as shall become apparent as the description proceeds, the invention resides in the construction, combination and arrangement of parts as shall be hereinafter more fully described, illustrated in the accompanying drawings, and pointed out in the claims hereunto appended.

The invention will be best understood and can be more clearly described when reference is had to the drawings forming a part of this disclosure wherein like characters indicate like parts throughout the several views.

In the drawings:

Figure 1 is a vertical section through the boiler with the pulsator plate on the bottom shown partly in elevation;

Figure 2 is a plan view of the perforated top plate;

Figure 3 is a sectional elevation of the pulsator plate; and

Figures 4 and 5 are enlarged fragmentary top and bottom plan views thereof, respectively.

This improved steam generating wash boiler may assume a number of various forms and designs but the essence of the invention lies in so fashioning it that the steam or water vapor

5 forming on the bottom of the accommodating vessel is collected or accumulated briefly by a wash-supporting plate resting loosely on the bottom of the vessel and released into the superposing mass of clothes and hot water in intermittent surges, the plate being simultaneously agitated. Thus without use of a motor driven dolly or other mechanism, a gentle yet rapid, thorough and efficient detergence is obtained without risk of damage to the sheerest or most delicate fabric. Additional to the detergent action of the plate in vibrating agitation and steam surge emissions, the boiler is pressurized by the provision of a gasketed and locked on cover with suitable steam escape valve so that the pressure within the vessel may be raised with beneficial results.

In its preferred form, the wash boiler is seen to comprise a straight-wall, pail-like cylindrical vessel 1 with a slightly larger open top 2 formed by an exterior flange or outward offset 3 that gives a shoulder seat 4. A removable cover 5 substantially convex on its upper side and downwardly sunk to nest in the mouth of the vessel, affords a closure for the top thereof and to render it leak-proof, a suitable gasket 6 is provided. The cover is locked down with three circumferentially spaced, toggle take-up clamps 7 attached to the vessel and adapted to hook on over the rim of the cover 5. To prevent the pressure within the boiler exceeding a safe and predetermined pressure, a bleed valve 8 mounted in the cover affords the necessary outlet, being of either the "fixed" or "adjustable" type as desired.

Resting on the interior shoulder 4 and normally confined by the depressed, locked-on cover 5 is a perforated top plate 9 having a central handle 10 and some spaced peripheral notches 11, the latter being to pass correspondingly placed angle keepers 12 extending inwards from the vessel's wall just above the shoulder 4. So when the cover 5 is removed this perforated plate 9 may be independently held in the vessel by the keepers 12 against accidental displacement by partially rotating the same. It may thus serve to hold back the wash while draining off the water.

Resting loosely on the bottom of the vessel 1 and of substantially less diameter than the interior of the boiler so that it is free to bounce or vibrate therein is the steam-agitated, pulsator plate 15, designed also to emit intermittent surges of steam. This plate, tray or rack 15, supporting the clothes being washed has spaced openings therethrough from steam collecting chambers on its underside. The steam being gen-

2

erated on the bottom of the vessel 1 is temporarily trapped in these chambers, actually lifting the pulsator and agitating the superposed wash, compressing it between this base plate and the perforated top plate 9. Then as the pent up steam blows off, surging swiftly upwards through the funnelled openings in the plate, it settles back on the bottom while the strong, divergent dirt-loosening currents of steam and water gurgitate up through the clothes being laundered.

The specific pulsator plate 15 here disclosed is a cast aluminum disk with a depending annular skirt or flange 16 near its periphery and a concentric skirt or flange 17 near the center. Radial webs 18, joining these skirts or flanges divide the underside of the plate into a number of segmental shaped chambers 19 encompassing a central round chamber 20. Each chamber has an outlet 21 located substantially centrally thereof and extending up through the plate with a surrounding flared or funnel-shaped depending skirt 22, of less depth than the concentric annular flanges and webs 16, 17 and 18 respectively that divide the bottom of the plate into steam collecting chambers, so that such funnelled outlet skirts or flanges terminate a short distance above or clear of the vessel's bottom even when the plate 15 is resting thereon.

The upper side of the plate has flow-directing grooves 23 running more or less at right angles to radial lines from each of the segment outlets 21 to the circumference of the plate and, in the center, a pair of concentric circles 23a and 23b connected by diametrically disposed cross grooves as at 24.

This light, sturdy form of plate has been found satisfactory, proving very active in use at it vibrates, pitches and tosses and bounces under the intermittent trapping and emitting of the steam.

With the increased pressure and steam-activated pulsator plate, the wash capacity and speed of this boiler are increased substantially enhancing its utility and value.

From the foregoing description taken in connection with the accompanying drawings, it will be manifest that a wash boiler is provided that will fulfill all the necessary requirements of such a device but as many changes could be made in the above description and many apparently widely different embodiments of the invention may be constructed within the scope of the appended claims, without departing from the spirit or scope thereof, it is intended that all matters contained in the said accompanying specification and drawings shall be interpreted as illustrative and not in a limitative or restrictive sense.

What I claim as new and desire to secure by Letters Patent is:

1. A wash boiler for use under elevated steam pressure comprising a vessel, a valved cover securely locked thereon and a flat-topped, disk-like pulsator plate loosely resting on the bottom 5 of said vessel and serving as a clothes supporting platform; said plate having steam trapping formations on its underside with outlets therefrom and designed when steam is generated in said boiler to intermittently emit blasts of 10 trapped steam and to bounce and vibrate vigorously and thoroughly agitate the superimposed clothes.

2. The combination with the structure set forth in claim 1 wherein said vessel has an exteriorly 15 flanged shoulder near its top rim and a perforated top plate resting thereon and secured in place by said locked cover, the clothes superposing said pulsator plate being vigorously compressed against the underside of said perforated top plate on the bouncing of said pulsator plate.

3. The combination with the structure set forth in claim 1 of a perforated wash-confining, top plate releasably secured in the top of said vessel and against the underside of which the clothes 25 supported on said pulsator plate are thrown and compressed on the bouncing of said pulsator plate and wherein said vessel cover is upwardly convexed spacing it well above said perforated plate and affording ample accommodation for the water squeezed out of the clothes when so compressed.
